UNITED STATES PATENT OFFICE.

JOHN E. WARREN AND FRANCIS A. CLOUDMAN, OF CUMBERLAND MILLS, MAINE, ASSIGNORS TO S. D. WARREN & COMPANY, OF BOSTON, MASSACHUSETTS.

APPARATUS FOR THE RECOVERY OF SODA.

SPECIFICATION forming part of Letters Patent No. 380,670, dated April 3, 1888.

Application filed April 22, 1887. Serial No. 235,765. (No model.)

To all whom it may concern:

Be it known that we, JOHN E. WARREN and FRANCIS A. CLOUDMAN, both of Cumberland Mills, county of Cumberland, and State of 5 Maine, have invented an Improvement in Apparatus for the Recovery of Soda, of which the following description, in connection with the accompanying drawings, is a specification, like letters on the drawings representing like 10 parts.

This invention relates to an apparatus or furnace for reclaiming chemicals from the spent liquors of pulp-mill digesters, and is an improvement upon the furnace shown and described in United States Patent No. 319,956, dated June 16, 1885.

One of the features of our invention consists in providing the evaporating-chamber with, preferably, a series of screw-conveyers 20 located near the bottom or hearth of the said chamber, and by means of which the liquid, which in most cases will be of a sirupy consistency when it reaches the bottom of the said chamber, may be fed forward toward the inlet 25 to the rotary calcining or incinerating furnace.

Our invention further consists in providing the rotary calcining-furnace with an agitating device, herein shown as a screw-conveyer or worm, by means of which the soda or other 30 chemical therein may be detached from the walls of the said furnace, thereby preventing the inner walls of the furnace from becoming coated or lined with chemicals.

Another feature of our invention consists in 35 providing the combustion-furnace, near the outlet of the calcining-furnace, with a throat having a surrounding water-jacket through which the spent liquor is circulated before entering the evaporating-chamber, the said 40 spent liquor serving to somewhat cool the said throat, thereby permitting the latter to be made of iron and to be projected into the outlet of the rotary calcining-furnace, iron being the most desirable material from which 45 to construct the said throat, but which could not be used to advantage hitherto on account of the intense heat in the fire-chamber, the iron, if used in furnaces made hitherto without the hollow throat having liquid circulat- 50 ing therethrough, being burned out in short

time, thereby rendering necessary repairs, which occasioned delay and expense.

Figure 1 is a longitudinal section of our improved apparatus for reclaiming chemicals in spent liquors from pulp-digesters; Fig. 2, a 55 section on line x x , Fig. 1; and Fig. 3, a sectional detail showing the form of the water-jacketed iron throat, the section being taken on the line x' x' , looking toward the right.

The rotary calcining-furnace A, provided 60 with tracks a, running on pulleys a' and located between the evaporating-chamber A' and the combustion-furnace A², is substantially as shown and described in the patent referred to.

The combustion-furnace A², constructed in 65 the main of brick or other refractory material, is provided with a throat, a², made of iron, and having a surrounding water-jacket, a³, substantially as shown in Figs. 1 and 3, the said iron throat projecting into the axial outlet b' 70 of the calcining-furnace, and being shaped as a segment of a circle to form for the product in the calcining-furnace a discharge-passage between the chord b of the segment and the axial outlet b' of the said calcining-furnace, as 75 shown in Fig. 3, and described in the above-mentioned patent. The iron throat a² has connected to its water-jacket near its bottom a pipe, a³, communicating, as shown, with the bottom of a tank or reservoir, B, to contain 80 spent liquor, the said iron throat also having connected to its water-jacket near its top a pipe, a⁴, extended into the evaporating-chamber A', the said pipe a⁴ being shown as ex- 85 tended to near the rear wall of the said evap- 90 orating-chamber. The spent liquor containing the chemicals to be recovered flows from the tank B through the pipe a³ into the water-jacket of the iron throat, from which it passes through the pipe a⁴ into the evaporating-cham- 95 ber, it falling upon a tray, b¹, and thence upon a second tray, b², arranged zigzag to cause the liquor to pass over a large evaporating-surface, the said liquor descending from the tray b² upon the bottom of the evaporating-chamber. As 100 the liquor circulates around the water-jacketed iron throat, it is heated, and the iron of the said throat is cooled sufficiently to prevent it from being burned out.

The liquid issuing from the pipe a⁴ is heated 100

on its passage around the iron throat from its water-jacket, so that it readily yields up its water as it flows through the chamber A', thereby hastening the evaporation of the said liquid, so that when it reaches the bottom of the said evaporating-chamber it is substantially of a sirupy consistency.

The sirupy liquid on the bottom of the evaporating-chamber is fed forward from its rear end toward the discharge or outlet c of the said chamber by means of screw-conveyers c', driven by a belt, (not shown,) but which is passed about pulleys c² at one end of the said screw-conveyers outside the evaporating-chamber.

The discharge or outlet passage c is controlled by a valve or gate, (not shown,) in substantially the same manner as in the patent referred to.

The sirupy liquid fed into the rotary chamber A is calcined therein; and in order to prevent the soda or other chemical salts from adhering to the inner walls of the said calcining-furnace an agitating device is located therein.

The agitation device is herein shown as a screw-conveyer or worm, d, which is independent of the calcining-chamber and is free to move therein.

The screw-conveyer or worm d normally rests upon the bottom of the calcining-furnace, and as the latter is rotated the said screw-conveyer or worm is carried up on one revolution to a certain distance, when it falls back again.

The screw-conveyer or worm serves to cut off or detach the soda or chemical salt adhering to the inner wall of the calcining-furnace, the said screw-conveyer or worm at the same time feeding the soda or other chemical salt in the furnace forward toward the outlet, the said soda or other chemical salt passing from the calcining-furnace between the chord b and axial outlet b' and into a suitable receptacle (not shown) located beneath the said discharge or outlet; or the said soda may be discharged directly upon the floor.

The soda or other chemical salt in the calcining-furnace is freed from organic matter, which is burned off by the products of combustion from the furnace A², they passing through the calcining and the evaporating furnaces to the chimney. (Not shown.)

Instead of the screw-conveyer or worm d, we may employ any other agitating or detaching device, such, for instance, as a harrow provided with teeth to scrape the adhering salt from the walls of the furnace.

The combustion-furnace may be made stationary or movable with respect to the calcining-furnace, as desired.

As shown in Figs. 2 and 3, the chord b is made in two parts, forming an angle between them to enable the water leg or throat to be more clearly shown; but in practice the chord will preferably consist of but a single straight line or part.

We claim—

1. In an apparatus for recovering chemicals from the spent liquors of pulp-digesters, the combination, with a rotary calcining-furnace, of a combustion-furnace, provided with a metallic throat having a surrounding water-jacket and extended into the rotary calcining-furnace, and pipes connecting the said jacketed throat with the liquor-tank and evaporating-chamber, substantially as and for the purpose specified.

2. In an apparatus for recovering chemicals from the spent liquors of pulp-digesters, a rotary calcining-furnace, combined with a loose gravitating agitating device located therein, whereby the recovered chemicals are prevented from adhering to the inner walls of the said furnace, substantially as described.

3. In an apparatus for recovering chemicals from the spent liquors of pulp-digesters, a rotary calcining-furnace, a combustion-furnace provided with an iron throat having a surrounding water-jacket and extended into the calcining-furnace, and a tank, B, connected to the said jacketed throat, combined with an evaporating-chamber, also connected with the said jacketed throat, the spent liquors being circulated around and heated in the jacketed throat before entering the evaporating-chamber, substantially as described.

4. In an apparatus for recovering chemicals from the spent liquors of pulp-digesters, a rotary calcining-furnace, and a combustion-furnace provided with a water-jacketed iron throat extended into the calcining-furnace, combined with an evaporating-chamber provided with screw-conveyers located near the bottom thereof to feed the chemicals forward toward the calcining-furnace, substantially as described.

5. In an apparatus for recovering chemicals from the spent liquors of pulp-digesters, a rotary calcining-furnace, an independent agitating device located therein, and a combustion-furnace provided with an iron throat extended into the calcining-furnace, and having a surrounding jacket, combined with an evaporating-chamber provided with screw-conveyers located near the bottom thereof to feed the chemicals forward toward the calcining-furnace, substantially as described.

6. In an apparatus for recovering chemicals from the spent liquors of pulp digesters, the combination, with a rotary calcining-furnace, of a combustion-furnace provided with a metallic throat extended into the rotary calcining-furnace, said throat being surrounded with a hollow jacket adapted to contain a fluid, as and for the purpose specified.

In testimony whereof we have signed our names to this specification in the presence of two subscribing witnesses.

JOHN E. WARREN.
